UNITED STATES PATENT OFFICE.

JOHN C. SHIRLEY, OF HUBBARD WOODS, ILLINOIS.

DISTRIBUTING DEVICE.

1,155,763.

Specification of Letters Patent.

Patented Oct. 5, 1915.

Application filed December 4, 1913. Serial No. 804,563.

To all whom it may concern:

Be it known that I, JOHN C. SHIRLEY, a citizen of the United States, residing at Hubbard Woods, in the county of Cook and State of Illinois, have invented certain new and useful Improvements in Distributing Devices, of which the following is a specification.

In the distribution or assorting of papers or letters when there are numerous compartments in which the material must be placed, much time is lost in the distribution of the papers by reason of the fact that all of the compartments are not so located relative to a single point that they may be conveniently reached by an operator. The first object of my invention, therefore, is to provide a distributing device with the compartments so arranged that the material to be filed may be placed therein by a single operator, and yet a large number of compartments may be employed without requiring the operator to shift his position to any material extent.

As all papers distributed within the separate compartments are not of the same size, and since the papers in each compartment are usually filed together, the usual method of getting papers of different sizes in position to be filed is to shake them down or otherwise arrange them so that a corresponding corner of all the papers is together, whereupon the papers may be bound through or by means of one corner. The shaking down, however, of papers of different sizes and of different grades, is in no wise a certain method, and frequently an important paper becomes lost merely because its frictional contact with adjacent papers prevents it from slipping into registering position, and when the papers are bound or filed the corner of each paper is not caught with the corners of the other papers and even if not lost the misplaced paper cannot be turned to readily.

Another object of my invention, therefore, is to so form a compartment in a distributing device whereby the papers when placed in said compartment will assume a position with one corner of each paper in registering alinement with one corner of every other paper, and when the papers are removed from the compartment they are in position to receive the binder or clip without the shaking down process as heretofore mentioned.

Still a further object of my invention is

to obtain a compartment wherein one corner of each paper filed therein will extend to one corner of the compartment so that all of the papers in one compartment have one corner in registration with one corner of every other paper filed therein so that filed papers of assorted sizes may be conveniently held or bound whereby they may be readily referred to and turned in the same manner as the pages of a bound book.

A distributing device embodying the novel arrangement of the compartments whereby each compartment is in near proximity to the operator, and a large number of compartments may be embodied in a single distributing device, and the further novel feature of providing means whereby the corners of the papers will be in registering alinement, produces a very desirable and efficient distributing device as shown in the accompanying drawing, in which—

Figure 1 is a perspective view of my improved distributing device; Fig. 2 is a transverse section of any one of the compartments; Fig. 3 is a longitudinal section of any one of the compartments; Fig. 4 is a cross-section of a modified form of compartment.

Referring now more particularly to the drawing, the distributing device comprises a plurality of compartments and as each compartment is substantially the same, as shown in the accompanying drawing, a description of one will serve for all.

A compartment consists of the side walls 4, and walls 5 and a bottom wall 6. The bottom wall is angularly disposed being attached to one of the side walls near its top edge and to the other side wall near the bottom edge. A stop 7 is placed at one end of each compartment so as to prevent any papers placed therein from curling up over the edge or falling out of the compartment. These compartments are so arranged that the bottom wall is not only angularly disposed between the side walls but the bottom walls are further inclined by having one end of the compartment higher than the other end so that one corner of each compartment is lower than the other three corners. The angular arrangement of the compartments is best shown in Fig. 1 wherein a plurality of compartments are arranged in sections, compartments 8, 9, 10 and 11 comprising one section and compartments 12, 13, 14 and 15 comprising another section. The compart-

ments 8 and 12 have a relatively slight longitudinal inclination of their bottom walls but sufficient, however, to accomplish the objects of the invention. Compartments 9 and 13 and 10 and 14 are arranged at substantially the same angle as each other but a greater longitudinal angle of inclination being given to their bottom walls than the compartments 8 and 12; whereas the compartments 11 and 15 are arranged at a still greater angle, nearer the vertical, than are compartments 10 and 14, so that it may be said that the super-imposed compartments of each section are arranged substantially on an arc of a circle or cylinder and the top compartments 11 and 15 thereof are, consequently, nearer the lower compartments 8 and 12 than they would be if their bottoms were disposed in the same plane as the bottoms of compartments 10 and 14.

The center section of compartments comprising three rows of three compartments each, has a bottom row of compartments 16 set back from the compartments 8 and 12 to provide an entrance space 17 for the operator. The bottom walls of the compartment 16 are arranged at a greater horizontal angle than the bottom walls of the compartments 8 and 12, but at a less angle than the bottom walls of the compartments 9 and 13 and are slightly lower than the compartments 9 and 13 so as to bring the compartments 18 and 19 near the entrance space 17 where the operator stands. The bottom walls of the compartments 18 and 19 are arranged in substantially the same plane but at an angle more near the vertical than are the bottom of the compartments 10 and 14.

If the compartments so far described are not sufficient in number, additional compartments may be added to the distributing device, such as the compartments 20, 21 and 22 forming a fourth section but so arranged that they are readily accessible to the operator standing in the space 17 and are preferably upon the right hand side of the cabinet for the reason that the average operator distributes with the right hand. The bottom walls of the compartments 20, 21 and 22 are disposed at such an angle as to bring them conveniently within the reach of the operator.

Each compartment may be provided with a stop 7 as heretofore described.

It is sometimes necessary to fold papers before filing and for this purpose I provide my device with folding boards 23 so positioned that they may be conveniently used by the operator and at the same time serving to brace three of the compartments and affording a sharp edge around which a paper may be folded.

It will be readily seen by the arrangement of the compartments that a large number of compartments may be used in a single dis-

tributing device and every compartment is within easy reach of the distributor standing within the space 17. It will furthermore be seen that as the bottom wall of each compartment is arranged at two angles, 70 papers placed within the compartment will gravitate to one corner only, consequently, when the papers are thus distributed and it is desired to bind the same together for filing, one corner of every paper within each compartment is in the same corner relatively with the corresponding corner of every other paper and, consequently, the papers may be removed from any compartment and bound in their removed position without the necessity of shaking them down to bring the corners into registering alinement.

While I have herein shown all of the bottom walls of the compartments so arranged that the lower left hand corner of each compartment is lower than the other three corners of each compartment, nevertheless, I do not wish it to be understood that I am limited to such arrangement, as the compartments may be so made that either the left 90 hand or right hand lower corner may be lower than the other three corners according to the method of filing adopted by the operator.

In Fig. 4 I have shown a modified form of 95 construction wherein one side wall meets the bottom wall at a right angle herein shown as formed by a block 23 abutting against one side wall and having its side 24 arranged at right angle to the bottom wall 6. Such a 100 construction brings the corner edge at a right angle to the planes of the side surfaces of the file papers.

As it is expected to bind or otherwise 105 secure the papers at the lower right hand corner of the same, the cabinet as shown herein is designed to receive the files with the upper surface of the papers down so that the lower right hand corner of each 110 letter will fall in the lower left hand corner of each compartment, but if the filing system is such that the operator desires to file the papers with the written matter facing upward, then the compartments should be 115 so made as to bring the lower right hand corner of each compartment in the lowest position.

Having now described my invention, I claim:

1. A distributing device having side and 120 bottom walls and the bottom wall disposed at two angles whereby one corner of said bottom wall is lower than the other three corners.

2. A cabinet comprising a plurality of 125 compartments arranged in adjacent sections, two of said sections comprising like arranged compartments super-imposed and having their bottom walls arranged in different planes, the center section having its com- 130

partments super-imposed and set back from the side sections and the bottom walls of each center section being arranged in different planes to each other and from the planes 5 of the bottom walls in the adjacent sections, and a fourth section disposed adjacent one of the end sections and comprising a plurality of super-imposed compartments arranged transversely relative to the side sections.

10 3. A cabinet comprising a plurality of compartments arranged in adjacent sections, two of said sections comprising like arranged compartments super-imposed and having their bottom walls arranged in different planes, the center section having its compartments super-imposed and set back from the side sections and the bottom walls of each center section being arranged in different planes to each other and from the planes 15 of the bottom walls in the adjacent sections, and a fourth section disposed adjacent one of the end sections and comprising a plurality of super-imposed compartments arranged transversely relative to the side sections and a folding board within the recess formed by 20 setting back the center section.

25 4. A cabinet comprising a plurality of compartments arranged in three adjacent sections, the middle section being set back

from the side sections, and each section comprising a plurality of super-imposed compartments having their bottom walls arranged at different angles and the bottom wall of each section being disposed at two angles whereby one corner of said bottom 30 wall is lower than the other three corners. 35

5. A cabinet comprising a plurality of compartments arranged in three adjacent sections, the middle section being set back from the side sections, and each section comprising a plurality of super-imposed compartments having their bottom walls arranged at different angles and the bottom wall of each section being disposed at two angles whereby one corner of said bottom 40 wall is lower than the other three corners, and a stop adjacent to the top of the lower wall of each compartment. 45

6. A distributing device having side and bottom walls and the bottom wall disposed at two angles whereby one corner of said bottom wall is lower than the other three corners, one of said side walls being arranged at a right angle to said bottom wall. 50
